United States Patent Office

Des. 186,054
Patented Sept. 1, 1959

186,054

SPOON OR SIMILAR ARTICLE

Lloyd E. Ressegger, Oneida, N.Y., assignor to General Mills, Inc., a corporation of Delaware

Application February 11, 1959, Serial No. 54,567

Term of patent 14 years

(Cl. D54—12)

FIG. 4

FIG. 5

FIG. 6

Fig. 1 is a front elevational view of a spoon showing my new design;

Fig. 2 is a side elevational view of the spoon;

Fig. 3 is a rear elevational view of the spoon; and

Figs. 4, 5 and 6 are partial sections on the respective lines 4—4, 5—5 and 6—6 of Fig. 1.

The essential features of my design reside in the handle portion as shown in full lines.

I claim:

The ornamental design for a spoon or similar article, substantially as shown and described.
